C. S. BURTON

CONTAINER FOR MUSIC ROLLS AND THE LIKE

Original Filed Jan. 21, 1921

Patented Aug. 11, 1925.

1,548,977

UNITED STATES PATENT OFFICE.

CHARLES S. BURTON, OF OAK PARK, ILLINOIS.

CONTAINER FOR MUSIC ROLLS AND THE LIKE.

Application filed January 21, 1921, Serial No. 438,885. Renewed October 27, 1924.

To all whom it may concern:

Be it known that I, CHARLES S. BURTON, a citizen of the United States, having residence at Oak Park, in the county of Cook and the State of Illinois, have invented certain new and useful Improvements in Containers for Music Rolls and the like, of which the following is a specification, reference being had to the accompanying drawings, forming a part thereof.

The purpose of this invention is to provide an improved container for such articles as music rolls and the like which may be inserted endwise longitudinally into a container of tubular character and retained by an end closure, the specific purpose of the invention being to provide a suitable, effective and conveniently operated releasable catch for holding the closure in position to retain the contents, subject to release and withdrawal of the closure for the removal of the contents, and further specifically adapted to initially expel the contents far enough to permit engagement by the hand of the operator for further withdrawal. It consists in the elements and features of construction shown and described, as indicated in the claims.

In the drawings:

Figure 1 is a longitudinal vertical section of a container embodying this invention, the music roll being indicated therein.

Figure 2 is a longitudinal vertical section of the structure shown in Figure 1 with the closure withdrawn for withdrawing the contents.

Figure 3 is a detail section at the line, 3—3, on Figure 4.

Figure 4 is a horizontal section at the line, 4—4, on Figure 1, the check strap being broken away to disclose the parts underneath.

In the structure shown in the drawings, 1 is a tubular container having one end closed and the other end open. 2 is a telescoping closure for the open end of the container, 1. This closure is open-topped and has the sides 2^a extended inwardly beyond the bottom shown at 2^a, and cut away obliquely at the upper edge for the purpose of permitting the closure to tilt to open position and be checked at that position shown at Figure 2. This feature of construction is not a part of the present invention, being shown in my co-pending appli-

cation No. 347,404, filed December 26, 1919.

3 is a check strap for limiting the withdrawal of the closure at the point at which it may tilt over the forward end of the bottom side 1^a of the container as shown in Figure 2, to permit the withdrawal of the contents. This check is a strap put through a slit, 1^a, at the bottom side of the container, the end being glued down onto the outer face of the said bottom, covering and concealing an aperture, 1^b, in said bottom which serves as a means of engaging the catch as hereinafter explained. The forward end of the check strap, 3, is engaged through a slit at 2^c in the bottom of the closure and folded rearward and glued down upon the bottom side of the closure, said strap passing over and serving to mask the catch device as hereinafter explained.

The catch for engaging with the container at closed position is a strip of flat spring metal, 4, which is lodged upon the bottom of the closure, and for positioning it definitely has the forward end up-bent at 4^a to stop against the inner side of the forward end 2^c of the closure, the rear end being bent down at 4^b to constitute the catch nose which engages the slot, 1^b, above mentioned, in the bottom of the container, positioned at such distance back from the forward open end of the container that the catch nose will reach said slot when the closure is at closed position as seen in Figure 1. The form of the catch and its dimensions are such that, normally, being lodged as described upon the bottom of the closure and with the up-bent end stopped against the forward end of the closure, the catch nose projects downward sufficiently for engaging the slot, 1^b, as seen in Figure 1. For disengaging it a pull, 5, is provided which is connected to the catch at the upper side thereof, extending thence forward and emerging through the forward end of the closure, and there provided with a flexibly connected lug, 6, which may be engaged by the operator as shown by the dotted line representation of the thumb and finger of a hand engaging it in Figure 1, for pulling forwardly. Said forward pull tends to pull upward the rear end of the catch and lift the catch nose out of the slot, 1^b, the catch being in that operation flexed to a position shown in dotted line in Figure 1, and tending to react resiliently to its original posi-

tion for re-engaging the slot. The pull, 5, preferably consists of a wire member folded to form two arms, 5^a, 5^a, extending from a short middle neck portion, 5^b, and having the rear ends of said arms bent at right angles to terminate projecting toward each other for pivotal engagement with the catch, 4. For such pivotal engagement the catch, 4, is folded at a short distance rearward from the catch nose as seen at 4^c, the fold forming an eye, 4^d, for engagement of the pivot ends, 5^e, of the pull, 5; and said up-bend, 4^e, constitutes an upraise in the catch which operates as a lever arm of the catch to cause the direct forward stress of the pull, 5, to lift the catch nose, as would not reliably happen if said pull, 5, were connected so as to cause the stress to operate directly in the plane of the catch at its lodgment on the bottom of the closure. To further facilitate this lever action, the emergence of the pull 5, through the up-bent end, 4^a, of the catch and through the forward end of the closure is accommodated by apertures, 4^e, in said up-bent end at a distance above the angle or bend, substantially as great as the height of said up-raise, 4^e, and the slot 2^a in the end, 2^e, of the closure at a position registering with said apertures. The lug, 6, pivotally engaged with the neck, 5^b, between the two arms, 5^a, of the pull is formed of any suitable material adapted to be folded to engage said neck after the latter has been thrust through the aperture, 2^b; and said lug being of dimensions greater than said aperture serves as a lock for retaining the pull, and thereby retaining the catch, in operative position in and with respect to the closure, 2, and dispensing with any other means of attaching said catch and pull to the closure; for it will be readily understood that the dimensions of the pull from its pivotal connection with the catch to the neck are such with respect to the corresponding dimensions of the catch that when the latter is at normal position unflexed, its stiffness is such that it holds the neck and the lugs thereon quite snugly or closely up against the outer face of the forward end of the closure, as seen in Figure 1, thereby holding said end engaged and slightly clamped between said lugs and the up-bent end, 4^a, of the catch; so that the resilient reaction of the catch tends to position it by means of its up-bent end or foot 4^a, seating squarely against the inner face of the forward end, 2^a, of the closure. As indicated, the line of stress of the pull is directly from the apertures, 4^e, in the up-bent end of the catch to the pivot eye, but in order to avoid intruding upon the space which should be occupied by the contents of the container as for example the music roll, A, or its head, A¹, both the arms, 5^a, 5^a, of the pull are bent at 5^f, and 5^g, at short distance from

the pivot end and from the up-bend, 4^a, of the catch respectively, to cause the portion of said arms between said bends to extend close to the bottom of the closure where they do not interfere with the head of the roll to any material extent. It will be understood that the wire of which the pulley is composed is sufficiently stiff so that these bends will not interfere with the direction of the stress incurred by the pull upon the catch at the eye at the upper end of the lever up-raise, 4^e.

A specific purpose of this invention being to provide a container for music rolls of such character that when said containers are accumulated in a pile as is a common method of arranging them in use, or on the shelves of the seller as merchandise, the roll may be withdrawn from the container without removing the container from the pile if so desired; or when it is desired, the container may be withdrawn bodily from the pile without opening it or for withdrawing the roll therefrom; and the catch described is especially designed with a view to serving this purpose. When the roll is to be withdrawn from the container without withdrawing the container from the pile, the operator will take hold of the lug, 6, between thumb and finger with the thumb pressing against the forward end of the closure as indicated in Figure 1, and thereby the catch will be withdrawn as shown in dotted lines in Figure 1 without any forward pull being exerted upon the container as a whole, and while holding the catch thus withdrawn by means of the thumb and finger as indicated, the operator will withdraw the enclosure for removing the roll. When it is desired to withdraw the container bodily from the pile, the operator will seize the lugs between thumb and finger as shown in Figure 3 without pressing the thumb against the end of the closure; and by direct pull in the direction of the arrow on Figure 3, the box will be withdrawn bodily from the pile, because in that action the catch is not lifted but is pulled, against the resistance caused by the friction of the container in the pile, to the forward side of the slot, 1^b, as seen in Figure 3, and engages with said forward end so as to pull the box bodily, as stated.

It is important in a device of this kind and for this purpose that the withdrawal of the closure should not only expose the roll but should withdraw it far enough so that it may be easily taken hold of for completing its removal. The up-raise, 4^e, which constitutes the lever arm of the catch, serves the purpose of engaging the head of the roll, as shown in Figure 2, a short distance, in the withdrawal of the closure as shown in that figure. In order to make this up-raise effective for that purpose, it is positioned at a distance forward from the catch nose, 130

though for the mere purpose of a lever arm it is not required to be at such forward position.

I claim:—

- 5 1. A container for the purpose indicated comprising a tubular outer member having an open end; an open-top closure for said end adapted to slide telescopically into the container; a spring catch mounted within 10 the closure extending along the bottom thereof from the outer end to a point near the inner end held to the closure at the forward end, having a catch nose at the inner end and free to be sprung up from the bottom 15 of the closure at said inner end, the lower side of the container having means for engagement of said catch nose at the in-thrust position of the closure, and a pull engaged with the upper side of the catch toward the 20 inner end thereof, said pull extending back along the catch above the same to and out through the forward end of the closure for manual operation to disengage the catch nose by springing its inner end upward by 25 stress exerted longitudinally of the catch.

2. In the construction defined in claim 1, the catch having an up-raise for attachment of the pull for affording leverage to lift the catch nose by longitudinal stress on the 30 catch.

3. In the construction defined in claim 1, the catch being formed with a right angular up-bent forward end for stopping against the forward end of the closure, and the pull being extended through said up-bent end for obtaining bearing and guidance 35 therein.

4. In the construction defined in claim 1, the pull having a flexibly connected lug at 40 the end outside the closure, said lug exceeding the dimension of the aperture in said end through which the pull emerges; whereby the lug serves as a locking means for holding the catch to the closure.

5. In the construction defined in claim 1, the catch having an up-bent forward end

which stops the catch against the forward end of the closure, said up-bent end being apertured for emergence of the pull through it, the pull having at the outer end a flexibly 50 connected lug whose dimensions exceed the dimensions of the aperture in the closure end and the aperture in the up-bent end of the catch through which the pull emerges, whereby the lug serves as the locking device 55 for holding the catch to the closure, the length of the pull being related to the length of the catch from the forward engagement of the pull therewith to the up-bent end so that the lug is held against the outer face 60 of the closure end, subject to withdrawal by up-tilting the catch at the free end for disengagement of the catch nose.

6. In the construction defined in claim 1, a check strap to limit the withdrawal of the 65 closure attached to the container bottom rearwardly beyond the catch-engaging means, and extending thence over the catch and at the forward end attached to the closure bottom at opposite sides of the catch; 70 whereby said check strap masks the catch to prevent its engagement with the container contents in their insertion and withdrawal.

7. In the construction defined in claim 1, the catch having an up-raise at a distance 75 forward from the catch nose for engaging the container contents and initially withdrawing the same in the opening movement of the closure.

8. In the construction defined in claim 1, 80 the catch having an up-raise for attachment of the pull affording leverage to lift the catch nose by longitudinal stress, said up-raise being at a distance forward from the catch nose to adapt it for engaging the container contents to withdraw the same in the 85 opening movement of the closure.

In testimony whereof, I have hereunto set my hand at Chicago, Illinois, this 7th day of August, 1920.

CHARLES S. BURTON.
